PAPER MACHINE REEL STARTER

Foster D. McCormack, International Falls, Minn., assignor to Minnesota and Ontario Paper Company, Minneapolis, Minn.

Application January 15, 1954, Serial No. 404,277

2 Claims. (Cl. 242—65)

This invention relates to a means for continuously winding rolls of material and has for an object to provide means for changing the winding material from a completed roll to a fresh roll without interruption in supply or change of speed in the winding material.

Many forms of machines are adaptable to produce and operate on a continuous web. Such machinery will naturally discharge the web in a continuous operation. In order that the web may be wound and practicable quantity upon separate reel it is necessary to discontinue the winding upon a reel which has received a predetermined quantity and to initiate winding upon an empty reel without stopping the continuous operation of the web producing or treating machinery. For example, in the paper industry a paper making machine produces a continuous web of paper and under ideal conditions a machine will not be shut down for several days. Similarly, paper coating machines are more efficiently run in a continuous manner and to this end paper may be supplied to them from a succession of reels which are so handled so as to splice the leading end of the uncoated paper to the trailing end of the spent reel. These splices may be made by any of the well known flying slice mechanisms and unless it is necessary to stop the machine for purpose of change of reels, the coating operation may be continuously performed in either of these examples as well as in any other instance. It is highly desirable to provide instantaneous transfer of the web from one winding reel to another.

Various types of reeling devices are known which are capable of handling a continuous moving web. One widely used form is known throughout the paper industry as the "Pope reel." Such a reel is shown in United States Patent No. 1,248,542. The present invention is particularly adaptable for use in conjunction with the Pope reel although, obviously, it is not limited in its use to such reel. For the purpose of description the invention will be set forth in connection with the Pope reel.

In general the Pope reel comprises a driving drum which is rotated at a peripheral speed equal to the speed of movement of the web with which it is to be used. Empty reels are placed into frictional contact with the surface of the driving drum and the leading end of the paper is secured in some manner to the empty reel whereby rotation of the driving drum will serve to rotate the empty reel and wind the paper therearound. When a predetermined quantity of paper has been wound upon the reel, it is necessary to shift the filled reel while it continues to wind to a position permitting the insertion of a new empty reel.

At this time the web is severed along a line just beyond the empty reel and the leading edge thus formed is directed upwardly around the empty reel. The directing of the web may be accomplished by the use of jets of air or water or steam, or may be accomplished by some mechanical manipulation or even by manual manipulation. Assuming a manual manipulation, the leading edge is gripped by the operators at opposite sides of the machine

2

and thrown up and over the empty reel whereby the leading edge drops down upon the face of the paper progressing toward the reel. This serves to drag the leading edge into the nip between the winding reel and the driving drum and forms a bight having sufficient friction to secure the web to the winding reel. From this point on the web the paper will be progressively wound upon the reel.

At an appropriate time the partially wound reel may be moved along the periphery in the direction of rotation thereof and brought to rest in a suitable bearing mechanism wherein it continues to wind in order to accumulate the predetermined quantity of web material. In the meantime a new empty reel is brought into position and is suspended just above the driving drum in a position ahead of the reel upon which the web is being wound. When the predetermined quantity is reached, it is necessary to sever the web at a point between the empty reel and the filled reel and it is necessary to direct the leading edge of the web around the empty reel to initiate winding upon the same.

The usual steel roll used as empty reels has been replaced by a rubber covered roll. The rubber covered roll has many advantages among which is no scoring or marking of reel drum surface. When the empty is lowered onto rotating reel drum, the friction often breaks the web. This web breaking results in considerable loss of paper.

Accordingly, it is an object of this invention to provide means for bringing the empty reel to substantially the same peripheral speed as that of the driven reel drum.

Other and further objects of the invention and the advantages of the same will be pointed out hereinafter and indicated in the appended claims or will be obvious to one skilled in the art upon understanding the present disclosure.

While one embodiment of the invention has been described in more or less detail to comply with the requirement of the statute, it is nevertheless desired that the detailed description be considered merely as illustrative and not as limiting.

In the drawings wherein similar parts are identified from similar characters of reference throughout the views Figure 1 is an end view with parts broken away of a winding device embodying the present invention and Figure 2 is a side view of the apparatus shown in Figure 1 with portions broken away.

The apparatus herein shown comprises a more or less conventional winding drum which is suitably rotatably mounted through the agency of a shaft such as indicated at 12 which extends from its opposite ends. A paper web 14 which is being delivered from a paper making, calendering or other paper treating apparatus is delivered over said winding drum 10 and is wound upon the reel core 15 (similar to that shown in Patent No. 1,925,670) to form a reel of paper. The reel core having paper wound therearound is, of course, suitably supported as to maintain the circumference of the paper being wound thereon in engagement with the winding drum 10 in accordance with more or less common practice.

While one reel is being formed another rubber covered reel core 16 is suitably positioned above the paper web 14 and adjacent the winding drum 10. The core reel 16 is provided with shafts 18 extending from opposite ends thereof. Member 30 is mounted on shaft 18 upon which is suitably mounted reel coupling 22. The reel core 16 is supported by reel bearing block 24. This block is shown in Figure 1 and such a block has performed highly successfully in operation. The block 24 is supported by member 26 which is carried by frame member 28. Mounted on shaft 12 and adapted to rotate therewith is belt sheave 30. Supported by member 36 adjacent its upper end is a three grooved sheave 32. The sheave 32 is

rotatably mounted upon suitable shaft 34 which is carried by member 26 at 36.

Pivottably mounted on shaft 34 is arm 38 and adjustably mounted on one end of the arm 38 is sheave support member 40. The distance between the sheave 32 and the sheave 44 can be varied according to the need. The arm 44 has extending therefrom shaft 42 which rotatably carries the sheave 44. Connected to the arm 38 at 46 is air cylinder piston rod 48. This piston rod is operatively mounted in air cylinder 50. One end of the air cylinder 50 is hingedly connected to clevis 52 at 54. Air lines 56 supply air to cylinder 50 and these air lines have mounted therein air flow control valves 58 and a four-way air cylinder valve 60. The air cylinder valves 60 have connected thereto air supply line 62 and exhaust port 64. The sheave 30 is adapted to drive by suitable means such as V-belt 66, the sheave 32 which in turn rotates sheave 40 through the medium of V-belts 68 and 70.

When the reel core 16 is in position shown in Figures 1 and 2, the sheave 44 and the V-belts 68 and 70 are in the position shown in dotted lines in Figure 1. When core 15 has received approximately the predetermined amount of paper and the paper is to be changed to a new reel core, the reel core 16 is brought up to substantially the same peripheral speed as the reel drum 10. This is accomplished by forcing the V-belts 68 and 70 into contact with reel coupling surfaces 22. The sheave 30 being driven by the shaft 12 imparts substantially the same speed of the wind drum to the reel core 16. When the paper is to be started upon the reel 16, this reel is lowered to the surface of the cylinder drum 10 by tilting the yoke 72 in the direction of the rotation of the drum 10. The reel bearing slides off the block 24 when the yoke 70 is tilted. The yoke 70 may be supported by the shaft 12 by member 74 and have yoke receiving block 76 mounted on shaft 18. To move the belts 68 and 70 from the position shown in dotted lines, Figure 1, air is admitted to the air cylinder 50 and the rod 48 is forced outwardly bringing the rotating belts into operating contact with the reel coupling surface.

It is to be understood that the V-belts may be replaced by any suitable driving means but V-belts have proven highly successful and economical in operation.

Typical of terms which may be applied to means upon which the paper is to be wound are the following reel, reel core, spool, mandril or spindle. The particular expression used in the specification is to be read as applying to any such members or to all of them.

What is claimed:

1. A paper winding apparatus comprising a driving drum, a means for rotating the driving drum, a rubber

covered winding roll normally disposed in contact with the driving drum so as to be driven thereby, means including vertically extending members attached to the winding apparatus frame, a sloping face block carried by said vertically extending members, said block initially supporting the said rubber covered winding roll out of contact with the driving drum, means for bringing the rubber covered roll to about the speed of the driving drum, said means including a sheave mounted on the driving drum, a second sheave supported by the vertically extending member and mounted above the first mentioned sheave and spaced to one side of a line extending perpendicular of the first sheave, a shaft carrying the second mentioned sheave, an arm having one end shorter than the other and pivotally mounted on said shaft, an adjustable sheave operatively attached to said arm, a sheave mounted on said sheave support, a fluid operated piston hingedly connected to the short end of said arm and the other end of said arm pivotally mounted on one of the vertically extending members, belt means rotating the sheaves and the said rubber covered winding roll and means for operating the fluid piston.

2. A paper winding apparatus comprising a frame for supporting a driving drum, a driving drum, means for rotating the driving drum, a rubber covered winding roll normally disposed in surface contact with the driving drum so as to be driven thereby, means including members attached to the frame and extending vertically therefrom, sloping face block members carried by the vertically extending members for initially supporting the winding roll out of contact with the driving drum, a sheave operatively mounted on the driving drum, a rigidly mounted sheave above the first mentioned sheave, an arm carried by said last mentioned sheave and having one end shorter than the other, a movable sheave mounted above the rigidly mounted sheave and adjustably supported by the longer end of the said arm, a fluid operated piston connected to said arm, a belt connecting the first and second sheaves and at least two belts connecting the rigidly mounted sheave to the movable sheave, said last mentioned belts adapted to bring the rubber covered winding roll up to the speed of the winding drum before the rubber covered roll comes into contact with the surface of the driving drum.
